AUTOMOTIVE VEHICLE BODY

James I. Harvey, Jr., 1117 119th St. SE.,
Lake Stevens, Wash. 98258

Filed Oct. 26, 1970, Ser. No. 25,642

Term of patent 14 years

Int. Cl. D12—08

U.S. Cl. D14—3

Fig. 1.

Fig. 2.

Fig. 3.

Fig. 4.

Fig. 7.

Fig. 8.

Fig. 9.

FIG. 1 is a top plan of an automotive vehicle body showing my new design.

FIG. 2 is a side elevational view thereof.

FIG. 3 is a front elevational view thereof.

FIG. 4 is a rear elevational view thereof.

FIG. 5 is a top perspective view thereof.

FIG. 6 is a rear elevational view thereof with doors open to reveal the interior.

FIG. 7 is a horizontal sectional view thereof taken along line 7—7 of FIGS. 8 and 9.

FIG. 8 is a vertical sectional view thereof taken along the line 8—8 of FIG. 7.

FIG. 9 is a vertical sectional view thereof taken along line 9—9 of FIG. 7.

The elements shown in broken lines are included for illustrative purposes only.

I claim:

The ornamental design for an automotive vehicle body, substantially as shown and described.
